United States Patent Office.

C. SHALER SMITH, OF BALTIMORE, MARYLAND, ASSIGNOR TO
SMITH, LATROBE, AND COMPANY, OF SAME PLACE.

Letters Patent No. 93,917, dated August 17, 1869.

IMPROVED CHORD FOR BRIDGES.

The Schedule referred to in these Letters Patent and making part of the same.

To all whom it may concern:

Be it known that I, C. SHALER SMITH, of Baltimore, in the county of Baltimore, and State of Maryland, have invented certain new and useful Improvements in the Construction of Chords for Bridges; and I hereby declare the following to be a full, clear, and exact description of the same, reference being had to the accompanying drawings.

The chord in which my invention consists, while intended more especially to meet the requirements of "deck-bridges," so called, is nevertheless adapted for use with any suitable system of bridge.

The object I have in view is to combine, in one chord, the excellent qualities of the cylinder to resist compression, and the similarly good qualities of the I-beam to resist transverse strain from the cross-ties or other superstructure. To this end,

My invention consists of a chord composed of a sectional tubular column of cast or wrought-iron, combined with an I-beam extending longitudinally, through the column, and dividing it into two parts, which are secured to said beam as hereinafter described.

In illustration of my invention, I have represented, in—

Figure 1, what is known as a four-segment "Phoenix column," combined with the I-beam, which extends the length of the column and through its axis.

Figure 2 is a transverse section of the same. The cylinder is divided by the beam-web into two equal parts, applied to each side of the beam, between its upper and lower flanges, and held in place by rivets extending through the flanges of the column and the intermediate beam.

Figures 3 and 4 represent a method of combining two beams when the column is of too great diameter to admit of one beam passing through it.

The column is an eight-segment Phoenix column, and as its diameter is too great for one beam, two are united, by setting the lower flange of the upper beam on the upper flange of the lower, the two flanges being then united by rivets, bolts, or other suitable means.

The construction of the chord does not vary in other respects from that shown in fig. 1.

These examples are sufficient to indicate the nature and value of my invention, and the manner in which the beam can be combined with a column of any diameter.

The form of the column itself is admirably adapted

to resist compression, while the capacity of the I-beam to resist transverse strain from the cross-ties of the deck-bridge or other superstructure is well known.

By thus combining these two qualifications, I produce a sandwiched chord, which is in every way better fitted for use than other chords heretofore employed for like purposes.

The use of the beam in this connection enables me to make the chord of less sectional area than would otherwise be required in order to resist the strain, the web of beam around the neutral axis of the chord being utilized, in order to bring the chord to the required standard.

Assuming that thirty inches of section is required for compressive strain, and ten inches for the transverse strain, there would be, theoretically, forty inches section required; but as the only practicable form of beam of sufficient depth to resist the transverse strain contains in itself twenty inches section, the chord, as ordinarily built, would contain fifty inches, while, by my improvement, I am enabled to place a compressive strain upon the surplus ten inches around the neutral axis of the beam, and thereby reduce the section of the cylindrical portion of the chord to twenty inches, thus using only the forty inches total section theoretically required.

I have represented, for the purpose of illustrating my invention, the I-beam, applied to a Phoenix column, but I do not wish to be understood as limiting myself to this special application. Any other form of column, whether of wrought or cast-iron, or steel, may be employed in lieu of the one represented, to which the beam can be applied in the manner hereinbefore specified.

Having now described my invention, and the manner in which the same is or may be carried into effect,

What I claim, and desire to secure by Letters Patent, is—

A chord, for deck and other bridges, composed of a sectional tubular column divided longitudinally by an I-beam, or a beam composed of two or more I-beams united, with which the sections of said tubular column are combined, substantially as and for the purposes set forth.

In testimony whereof, I have signed my name to this specification, before two subscribing witnesses.

C. SHALER SMITH.
